UNITED STATES PATENT OFFICE.

HENRY GROSSMAN, OF NEW YORK, N. Y.

DESIGN FOR A HAND-BAG.

No. 38,683.

Specification for Design.

Patented July 16, 1907.

Application filed June 20, 1907. Serial No. 379,995. Term of patent 7 years.

To all whom it may concern:

Be it known that I, HENRY GROSSMAN, a citizen of the United States, residing at New York, in the county of New York and State of New York, have invented a new, original, and ornamental Design for Hand-Bags, of which the following is a specification, reference being had to the accompanying drawing, forming part thereof.

The figure represents a perspective view of hand-bag embodying my design.

I claim:

The ornamental design for a hand-bag as shown.

HENRY GROSSMAN.

In presence of:

G. A. SPITZER,
MORRIS MATZNER.
